UNITED STATES PATENT OFFICE.

EMIL HORNSTEIN, OF VIENNA, AUSTRIA.

PROCESS OF MANUFACTURE OF SLABS OF COMPRESSED CORK.

1,407,655.

Specification of Letters Patent. Patented Feb. 21, 1922.

No Drawing.

Application filed July 13, 1914. Serial No. 850,626.

(GRANTED UNDER THE PROVISIONS OF THE ACT OF MARCH 3, 1921, 41 STAT. L., 1313.)

To all whom it may concern:

Be it known that I, Dr. EMIL HORNSTEIN, deputy-manager, subject of the Emperor of Austria, residing at Vienna, VI, 5 Köstlergasse 7, in the county of Lower Austria and State of Austria, have invented certain new and useful Improvements in Processes of Manufacture of Slabs of Compressed Cork, of which the following is a specification.

There is already known a process of manufacture of slabs of compressed cork for facing or covering, which process is characterized by pressing in a mould granulated cork that has been steamed or moistened with water, whereby there is produced a compressed cork slab, which is dried in the mould by warming, and is thereupon sawn into suitably thin plates. This process has, 15 however, a whole series of serious disadvantages. In order to obtain the requisite compactness in the structure of the final product, the slab of compressed cork has to be compressed with very great force, whereby 20 the subsequent drying process is rendered difficult, since the compact block, being a bad conductor, must be very highly heated from the outside if the heat is to penetrate to the inner part. In this process, the outer 25 edges of the slab are heated to such an extent that the cork substance in part undergoes chemical changes, whereby it assumes uneven colouring, this occurring even at a time at which the heat has not yet penetrated to 30 the interior sufficiently to drive off the humidity. Under such circumstances, there could be no hope of obtaining a constant quality of the final product. Moreover, the cutting up of a dried slab was not always 35 possible in a veneer machine, on account of its brittleness, but could only be effected by sawing, so that, as may easily be seen, there was a great deal of waste, which, in view of the comparatively small thickness of the 40 slabs to be produced, often amounted to 45 50%. In addition to that in the slabs thus obtained, an evenly close-grained and evenly coloured surface could not be produced at all.

Another method of manufacture of these plates is as follows:

They are separately produced in suitable moulds, by compressing the necessary quantity of cork. This process, however, has the

disadvantage that, even though it might 55 be considered as technically more perfect, it is economically less advantageous, as the manipulation required is much too expensive and too intricate. In order to improve this method economically, the slabs of cork 60 were also made of different qualities of cork, the bottom of the mould being first covered with a thin layer of the best cork substance, and coarser and therefore cheaper cork being then thrown on to this first 65 layer, so that when compression had been effected, a slab was obtained having a compressed surface of good cork. Apart from the fact that these expedients resulted in only a very slight increase in the economic 70 value of the intricate process, the products obtained had moreover the disadvantage that, as soon as the thin surface layer was worn through, the inferior cork was exposed, and the possibility of employing the 75 slab any longer was doubtful.

All the disadvantages mentioned above are avoided in the process according to the present invention. This process is as follows: A suitable number of thin layers obtained by dividing a slab of the compressed cork produced by low pressure and by a subsequent drying out, are placed one upon the other, and this pile is subjected to a higher pressure than that employed for 80 85 making the original slab. The compressed slabs thus obtained are then dried by heat, there being two ways of doing this. If drying operations are conducted at a low temperature in order to avoid changes in 90 the cork substance, the separate layers are stuck together by a suitable binding substance. If higher temperatures are employed, the binding substance is not necessary, as the products of distillation, given 95 off by the cork substance at high temperatures, will effect the junction of the separate layers.

This process is distinguished from that hereinbefore referred to, principally by the 100 fact that the primary compressed cork slabs are divided into thin layers, it being possible to effect this without any waste and without much difficulty, on a veneer machine. As many of the thin layers thus 105 obtained are placed one upon the other as are necessary for the production of the desired slabs, and if necessary, these layers

are connected together by a binding substance, such as for instance casein-resin cement, or any other waterproof cement. The slabs obtained by the compression of these 5 piles possess so little thickness, that they may be simply dried by a moderate amount of heat. Unlike those employed in other known processes, the moulds need not be closed on all sides, but only a top and a 10 bottom piece are required, between which the pile of cork slabs is placed; the advantage thus gained being that, since all the sides of the pile remain free, the moisture may escape unhindered. The single slabs 15 produced possess a very close and dense structure and are preferably smooth on their surface, they moreover demand much simpler manipulation in the process of manufacture than the plates referred to, which 20 had to be separately manufactured, from the putting of the granulated cork in the mould to the final compression.

In order to facilitate the compressing, the layers or piles may be steamed or moistened with water before pressing, whereby 25 they become more flexible. The slabs may also be made of layers of cork of different quality, the front being superior to the back, in order to make the product cheap. 30 The top, or perhaps the two top layers, may consist of substance of superior quality to the underneath layers and for this purpose, two different primary compressed cork slabs are produced, in order to obtain 35 layers of varying quality, which are then suitably formed into piles.

The steaming or moistening of the cork before pressing may be limited to the top layer, whether this be of better or the same 40 substance as the other layers; this top layer thus becomes more yielding, and when the whole is pressed, is reduced more than the other layers. Another advantage of this is that the cork slab retains more elasticity, 45 and moreover, as the under layers are less closely pressed together, a smaller quantity of cork is required to produce a given thickness.

In every case, cork slabs of extreme evenness and great resistance, with a perfectly smooth surface, are obtained and such slabs may be so easily and cheaply produced that they can compete with any wooden facing 50 of good quality, and will moreover be superior to the wood by reason of their special physical properties (excellent insulation against heat and sound, absolute constancy of volume etc.,) apart from the unique aesthetic effect.

60 What I claim is:

1. Process for manufacturing compact and solid slabs of compressed cork, consisting in forming by pressure a slab of compressed finely-divided cork; dividing said 65 slab into thin layers; forming said layers

into a pile; and subjecting said pile to pressure.

2. Process for manufacturing compact and solid slabs of compressed cork, consisting in forming by pressure a slab of compressed finely-divided cork; dividing said slab into thin layers; forming said layers into a pile; causing said layers to become sticky; subjecting said pile to pressure; and 70 drying the pile.

3. Process for manufacturing compact and solid slabs of compressed cork, consisting in forming a slab of compressed cork; dividing said slab into thin layers; forming said layers into a pile; causing said layers 80 by the action of heat to become sticky with the products of distillation; subjecting said pile to pressure; and drying the pile.

4. Process for manufacturing compact and solid slabs of compressed cork, consisting in forming at low pressure a slab of compressed cork; dividing said slab into thin layers; forming said layers into a pile; causing said layers to become sticky; subjecting said pile 85 to the action of a pressure higher than said low pressure; and drying the pile.

5. Process for manufacturing compact and solid slabs of compressed cork, consisting in forming a slab of compressed cork; dividing said slab into layers; forming said layers into a pile the topmost layer of which is of cork of a quality higher than that of the other layers of the pile; causing said layers to become sticky; subjecting said pile 95 to pressure; and drying the pile.

6. Process for manufacturing compact and solid slabs of compressed cork, consisting of the arrangement of a number of thin independent layers of pressed cork one upon the other, the steaming of said layers, the 105 pressing of said layers in their superposed position and the drying by heat of the pressed and compact layers, substantially as described.

7. Process for manufacturing compact and solid slabs of compressed cork, consisting of the arrangement of a number of thin independent layers of pressed cork one upon the other, the steaming of the top independent layer, the pressing of said layers, in their superposed position and the drying by 115 heat of the pressed and compact layers, the top independent layer being steamed in order to exert greater compression of the 120 said top layer during the pressing of the consolidated slab in order to obtain greater elasticity of the cork slab as a whole, substantially as described.

8. Process for manufacturing compact and solid slabs of compressed cork, consisting in forming a slab of compressed cork; dividing said slab into layers; forming said layers into a pile; causing said layers to become sticky; subjecting said pile to pressure 125

between top and bottom plates while leaving the sides free to permit the escape of moisture; and drying the pile.

9. Process for manufacturing compact and solid slabs of compressed cork, consisting of the arrangement of a number of thin independent layers of pressed cork one upon the other, the wetting of the top independent layer with water, the pressing of said 10 layers, in their superposed position and the drying by heat of the pressed and compact layers, the top independent layer being wet-

ted, in order to exert greater compression of the said top layer during the pressing of the consolidated slab in order to attain 15 greater elasticity of the cork slab as a whole, substantially as described.

In testimony whereof I affix my signature in presence of two witnesses.
